PANEL

Percy Solotoy, Los Angeles, Calif.

Application July 5, 1946, Serial No. 131,329

Term of patent 14 years

(Cl. D33—1)

To all whom it may concern:

Be it known that I, Percy Solotoy, a citizen of the United States, residing in Los Angeles, in the county of Los Angeles and State of California, have invented a new, original, and ornamental Design for a Panel, of which the following is a specification, reference being had to the accompanying drawing, forming part thereof.

Fig. 1 is a face view of a panel, showing my new design.

Figs. 2 to 5 are respectively, sections taken on the lines 2—2, 3—3, 4—4, and 5—5, of Fig. 1.

The dominant feature of the design resides in the association of blocks in which opposite plain sides of each block abut the sides of adjoining blocks that have rounded upper edge portions.

I claim:

The ornamental design for a panel, as shown and described.

PERCY SOLOTOY.
